UNITED STATES PATENT OFFICE

156,728

HAIR TEXTURE GRADER

Robert E. Grigsby, Cincinnati, Ohio

Application September 17, 1948, Serial No. 148,644

Term of patent 14 years

(Cl. D52—1)

To all whom it may concern:

Be it known that I, Robert E. Grigsby, a citizen of the United States of America, residing at Cincinnati, in the State of Ohio, have invented a new, original, and ornamental Design for a Hair Texture Grader, of which the following is a specification, reference being made to the accompanying drawing, forming part thereof.

Fig. 1 is a front elevational view of a hair texture grader embodying my new design; Fig. 2 is a side elevational view, and Fig. 3 is a top plan view of the same.

I claim:

The ornamental design for a hair texture grader, substantially as shown.
ROBERT E. GRIGSBY.
